RICHARDSON & PHILLIPS COMPANY, OF SEYMORE, IOWA, A CO-
PARTNERSHIP.

ATTACHMENT FOR CORN-PLANTERS.

No. 805,083.

Specification of Letters Patent.

Patented Nov. 21, 1905.

Application filed May 17, 1905. Serial No. 260,884.

To all whom it may concern:

Be it known that I, LEROY LINDSEY, a citizen of the United States, residing at Seymour, in the county of Wayne and State of Iowa, have invented certain new and useful 5 Improvements in Attachments for Corn-Planters, of which the following is a specification.

The object of this invention is to construct 10 a marking attachment for corn-planters comprising two bars each having a pivotal connection with the main frame and adapted to be moved to rest in the lengthwise direction of the main frame when not in use for transportation.

In the accompanying drawings, Figure 1 is a plan view of a corn-planter embodying my 15 improvements. Fig. 2 is a side elevation. Fig. 3 is an isometrical representation of the rear portion of the main frame as seen from its under face. Fig. 4 is an isometrical representation of the outer end of one of the marker-bars, and Fig. 5 is an isometrical representation of the pivotal connection of one 20 of the marker-bars with the stationary cross-bar.

The corn-planter shown in the drawings is of an old construction and comprises the main frame 1, supported by the axle 2 and 25 wheels 3. The runner-frame 4 supports the seedboxes 5 and runners or furrow-openers 6. The forward portion of the main frame has a pivotal connection with the runner-frame. A tongue 7 has a connection with the runner-frame.

30 The mechanism for operating the seed-dropping devices is not shown in the drawings, as it forms no part of my invention.

To the rear bar of the main frame is connected a cross-bar 8 by the bolt 9. To the under face of the cross-bar are secured plates 10, which rest against the under face of the rear bar of the main frame, which in conjunction with the bolt 9 serves to form a substantially fixed connection between the cross-bar 40 and main frame. Each end of the cross-bar supports an angle-bolt comprising the branches 11 and 12, located at an acute angle with respect to each other. The angle-bolt 45 at one end of the cross-bar has a connection with the bar 13 by the branch 12 of the bolt

passing through it. Nuts are placed on both ends of the bolt.

To the free end of the bar 13 is connected a marker-arm having a portion 14 secured to the under face of the bar by the bolts 16 and a portion 15 turned at an angle diagonally across the bar. This marker-arm is adjustable bodily in the lengthwise direction of the bar 13 by reason of the series of holes 26, receiving the bolts 16. In the free end of the bar 13 is located a cotter 17. To the other end of the cross-bar 8 is connected a bar 18 in the same manner as the bar 13 is connected. This bar 18 supports a marker-arm, also a 65 cotter 19. This marker-arm is adjustable in the lengthwise direction of the bar 18 by reason of the series of holes 20, receiving the bolts 21.

A sheave 22 is connected to the under face 70 of the tongue 7. A rope 23 has one end connected to the cotter 17, and its other end is connected to the cotter 19. This rope passes over the sheave 22 and has two knots 24 and 25, one located each side of the sheave. 75

With the parts in the position shown at Fig. 1 the arm 18 is turned so as to occupy a position lengthwise of the main frame of the planter, and the arm 13 is in an operative position. The knot 24 in the rope resting 80 against the sheave holds the arm 13 in proper working position. In moving the planter over the ground the portion 15 of the marker-arm 13 will form a depression in the ground, serving as a guide in planting. By the employment of the cotters should the bars or marker-arms strike an obstruction the cotters would pull out before the rope would break. By the employment of the angle-bolts for forming a connection between the cross-bar and 85 the bars supporting the marker-arms it will be seen that the bars have a vertical swinging movement, the branches 11 of the angle-bolts acting as centers, and in turning the bars into an inoperative position their free 90 ends will rise so as to free the ground. 95

I claim as my invention—

1. A marker for corn-planters comprising a main bar, and two marker-bars, one pivoted to each end of the main bar, the connection consisting of an angle-bolt, one branch 100 of the bolt connected to the main bar, and

the other branch of the bolt connected to the marker-bar.

2. A marker for corn-planters comprising a marker - bar, a cotter supported by the marker-bar, and a rope having one end connected to the cotter in order that the cotter may become disengaged from the marker-bar

when severe strain is applied to the marker-bar.

LEROY LINDSEY.
